134,403

DESIGN FOR A COMBINED COUNTER AND RULE

James Stanley Sutton, North Tarrytown, N. Y.

Application August 2, 1941, Serial No. 102,651

Term of patent 7 years

To all whom it may concern:

Be it known that I, James Stanley Sutton, a citizen of the United States of America, residing at North Tarrytown, in the county of Westchester, in the State of New York, have invented a new, original, and ornamental Design for a Combined Counter and Rule, of which the following is a specification, reference being had to the accompanying drawing, form a part thereof.

In said drawing:

Fig. 1 is a perspective view of a combined counter and rule showing my new design and Fig. 2

is a cross-sectional view taken as on the plane indicated by line 2—2 of Fig. 1.

The characterizing features of the design reside in the rule shown having serially numbered holes arranged in parallel rows along the body of the rule in association with the apertured substantially semi-spherical portions extending upwardly from the top surface thereof as shown.

I claim:

The ornamental design for a combined counter and rule, as shown and described.

JAMES STANLEY SUTTON.
